[57] CLAIM

The ornamental design for an organizer for hair curlers, as shown and described.

DESCRIPTION

FIG. 1 is a top, front perspective view of an organizer for hair curlers showing my new design;

FIG. 2 is a side elevational view thereof, the side opposite being a mirror image of the side shown; and

FIG. 3 is a rear elevational view thereof.

The opposite side of FIG. 1, not shown, is the same as and symmetrical to FIG. 2.
